UNITED STATES PATENT OFFICE.

FORREST A. HEATH, OF JERSEY CITY, NEW JERSEY, ASSIGNOR, BY MESNE ASSIGNMENTS, TO GEORGE WHYSALL, OF MARION, OHIO.

MIXING DEVICE.

1,153,915.

Specification of Letters Patent. Patented Sept. 21, 1915.

Application filed September 2, 1910, Serial No. 580,177. Renewed February 19, 1915. Serial No. 9,421.

To all whom it may concern:

Be it known that I, FORREST A. HEATH, a citizen of the United States, and a resident of the city of Jersey City, in the county of 5 Hudson and State of New Jersey, have invented certain new and useful Improvements in Mixing Devices, of which the following is a specification.

The object of this invention is to provide 10 an improvement in mixing devices for thoroughly mixing or commingling the elements in a mixture such as issues from the delivery port of a carbureter in order to make it homogeneous, prior to being introduced into 15 the cylinder of a hydrocarbon engine.

In application Serial No. 496,266, filed May 15th, 1909, in application Serial No. 590,266, filed November 2, 1910, (which is a division of application Serial No. 496,266), 20 and also in application Serial No. 538,041, filed January 14th, 1910, I have shown a mixing device having a casing and a rotatable member therein comprising a fan member and a wire mesh, which is parallel with 25 the path of rotation of the fan, for causing a disintegration of the particles of fuel in the mixture and a thorough commingling of the fuel with the rest of the mixture by a contacting of the wires in the mesh with the 30 fuel particles as the mixtures pass the mesh and at a time when the rotatable member is rotating.

It will be noted that the mixing device disclosed in any one of said applications 35 has only one mesh and therefore the wires in said mesh must be close enough together to cause a proper commingling and mixing of the fuel particles with the rest of the mixture as the mixture passes through the mesh. 40 It will furthermore be apparent that the greater the number of wires which are in the mesh, the more effective will be the commingling of the fuel particles with the rest of the mixture and at the same time correspondingly greater will be the resistance 45 of the passage of the mixture through the mesh.

In order to more effectively mix or commingle the fuel particles with the rest of 50 the mixture and at the same time decrease the resistance to the flow of mixture through the mesh, I have provided a plurality of spaced wire meshes in which the distances between the wires are comparatively great, 55 whereby the areas of the openings in the

mesh are comparatively large and accordingly the resistance to the flow of mixture therethrough is correspondingly small. At the same time I accomplish more effectively the mingling of the fuel particles with the 60 rest of the mixture by successively subjecting the mixture to the cutting action of the outwardly extending wires or members arranged along its path of travel.

It is to the above features that this in- 65 vention is particularly directed.

As showing a specific embodiment of my invention, reference is made to the accompanying drawing which forms a part of this specification and in which drawing— 70

Figure 1 is a plan view partly in section showing one form of mixing device; Fig. 2 is a sectional view taken on the line 2—2 of Fig. 1; Fig. 3 is a plan view of the rotatable mixing member utilized in the device shown 75 in Fig. 1; Fig. 4 is a plan view of the rotatable mixing member utilized in the device shown in Fig. 1 looking at the member from below; Fig. 5 is a plan view partly in section showing another form of mixing de- 80 vice; Fig. 6 is a sectional view taken on line 6—6 of Fig. 5; Fig. 7 is a plan view of the rotatable mixing member utilized in the de- 85 vice shown in Fig. 5; Fig. 8 is a plan view of the rotatable mixing member utilized in the device shown in Fig. 5 looking at the member from below.

Both forms of the device shown on the drawing are similar in that each comprises a casing and a rotatable mixing member 90 mounted therein comprising a fan and a plurality of spaced meshes, but the meshes shown in the forms illustrated in Figs. 1 to 4 have a different construction from that in the forms illustrated in Figs. 5 to 8. In the 95 form shown in Figs. 1 to 4 *a* designates the casing in which is revolvably mounted the mixing member *b* comprising the fan member *c* which serves as a propelling member, and spaced wire meshes *d* and *e* located 100 upon opposite sides of the fan blades. In this form the meshes *d* and *e* are composed of straight wires *f* and *g* and *h* and *k* re- 105 spectively which cross each other and it will be noted that all the wires which compose the meshes have sections which extend toward the periphery of the rotatable mixing member and that each of the wires will therefore have a cutting or chopping effect 110 upon the mixture which passes through the

mesh and will therefore cause a thorough mixing and commingling of the fuel particles with the rest of the mixture. The form shown in Figs. 5 to 8 has a casing α' and a revoluble mixing member b' which comprise a fan member c' which serves as a propelling member, and spaced meshes d' and e' located upon opposite sides of the fan member and revoluble therewith. The meshes d' and e' are formed respectively of wires f' and h' which extend radiately outward and concentric wire rings g' and k' .

The cutting or chopping effect upon the mixture is primarily caused by the outwardly extending wires f' and h' engaging the fuel particles in the mixture as the mixture passes through the mesh at a time when the mesh is being rotated by the fan. The function of the wires g' and k' is to hold the outwardly extending wires in place and the concentric rings g' have but little cutting or chopping effect upon the mixture and it is obvious that without departing from the spirit and scope of my invention that the concentric rings may be omitted provided the outwardly extending wires or members are rigid enough and secured so as to remain in place when the mixing member rotates.

It is obvious that various other forms and modifications may be made without departing from the spirit and scope of my invention.

I claim as my invention:

1. A mixing device for hydrocarbon engines comprising a casing and a rotatable fan member therein by which the mixture passes and outwardly extending disintegrating or cutting elements which are located at the opposite sides of the fan and rotatable therewith.

2. A mixing device for hydrocarbon engines comprising a casing and a rotatable blade propeller member therein by which the mixture passes and meshes secured to opposite sides of the propeller blades and rotatable therewith.

3. A mixing device for hydrocarbon engines comprising a rotatable blade propeller having spaced parallel meshes or screens secured thereto and rotatable therewith.

4. A mixing device comprising a rotatable member having propelling blades for caus-

ing rotation of the member and rotatable with the blades outwardly extending disintegrating wire members which are located 55 in the path of the mixed fuel and air which pass the propelling blades, the said outwardly extending members being spaced apart and located at different points along the axis of rotation of the rotatable member. 60

5. A mixing device comprising a rotatable member having blades and means carried by the member for engaging particles of fuel in the mixture passing over the blades, said means having wire members which extend 65 toward the periphery, said members arranged so that they traverse the mixture at different points along its path.

6. A mixing device comprising a rotatable member having outwardly extending blades, 70 disintegrating or cutting members located at opposite sides of the blade carried by the blade and extending toward the periphery of the same and means for supporting the rotatable member in the piping of a hydro- 75 carbon engine.

7. A mixing device comprising a rotatable member having blades, wire meshes carried by the member and located upon opposite sides of the blades, said meshes being flat 80 and lying in spaced parallel planes.

8. A mixing device comprising in combination a rotatable member having fan blades for propelling the same and located in the path of the mixture passing the fan 85 blades, said device also comprising rotatable flat spaced screens which are arranged at different places along the axis of rotation of said member.

9. A mixing device comprising a rotatable 90 member having fan blades, said member carrying spaced meshes having outwardly extending spaced elements, said meshes located in the path or flow of the mixture, the area of the opening of the meshes being 95 greater than the area occupied by the wires or members which form the meshes.

This specification signed and witnessed this 25th day of August, A. D., 1910.

FORREST A. HEATH.
